UNITED STATES PATENT OFFICE.

JOHN BRAUN AND FERDINAND BOHN, OF BUFFALO, NEW YORK.

WINDOW-GLASS FASTENER.

SPECIFICATION forming part of Letters Patent No. 316,940, dated May 5, 1885.

Application filed January 17, 1885. (No model.)

To all whom it may concern:

Be it known that we, JOHN BRAUN and FERDINAND BOHN, citizens of the United States, residing in Buffalo, in the county of Erie and 5 State of New York, have invented certain new and useful Improvements in Window-Glass Fasteners, of which the following is a specification.

The object of our invention is to provide a 10 simple and efficient means for securing glass to window-sashes, doors, &c., all of which will be fully and clearly hereinafter described, shown, and claimed by reference to the accompanying drawings, in which—

15 Figure 1 is an outside view of a window adapted to hold four lights of glass. Fig. 2 is an inside view of a window adapted for holding six lights of glass. Fig. 3 represents a window having an arched top and adapted for 20 one light of glass. Fig. 4 is an enlarged section through line X X, Fig. 2; and Fig. 5 represents an enlarged section through line Z Z, Fig. 1.

The window-frame a a' is made of wood or 25 other material in the usual way.

The frame-pieces a a' are each provided with grooves a^2 . (See Fig. 5.)

a^3 is a removable strip, having an offset or depression, a^4 , along its whole length, its form 30 in cross-section being similar to that shown at e above the dotted lines v in Fig. 5, so as to allow for the thickness of the glass when the strip is in place. It is secured in place by bolts a^5 , having countersunk heads. The nut por-

tion is provided with a square or diamond 35 shaped head, c' , or of any other shape to prevent it from turning around while operating the screw. It fits down within a depression in the strip a^3 .

In Fig. 3 we have shown an arched window-frame, the removable strip being also arched. This frame is adapted to receive a single glass; but they may be made to receive one or more glasses, as shown in Figs. 1 and 2.

In putting the glasses in place the strip a^3 45 is taken off and the glass is made to slide down in the grooves in the frame, and the removable strip is then put on, thereby securing the glass firmly in place.

We are aware that a window-sash provided 50 with grooves to receive the glass and a removable strip to secure it in place is not new. We therefore do not claim such, broadly; but

What we do claim is—

A window-sash provided with grooves a^2 , 55 in combination with a removable strip, a^3 , having an offset, a^4 , substantially as specified, and bolts for securing it in place, consisting of the nut portion having the diamond-shaped heads c' , adapted to fit in corresponding depressions in the removable strip, and the bolts a^5 , having countersunk heads, as and for the purposes described.

JOHN BRAUN.
FERDINAND BOHN.
